ELECTRODE FOR GASEOUS CONDUCTION DEVICES

Daniel S. Gustin, Bloomfield, N. J., assignor, by mesne assignments, to Westinghouse Electric and Manufacturing Company, East Pittsburgh, Pa., a corporation of Pennsylvania

Application July 11, 1935, Serial No. 30,778

8 Claims. (Cl. 176—126)

5 My present invention relates to discharge devices and has particular reference to an electrode therefor and constitutes an improvement over the electrode shown and described in my copending application Serial No. 757,658 filed December 15, 1934, assigned to the same assignee as the present invention.

10 Although an electrode constructed in accordance with my present invention may be utilized in various types of electrical devices it is particularly adaptable to discharge lamps employing metallic vapor as an ionizable medium. In lamps of the metallic vapor type it is customary to employ in addition to a small quantity of 15 vaporizable metal, such as mercury, sodium, cadmium or the like, one or more rare gases for facilitating starting of a discharge. During operation of these lamps the vapor pressure thereof may be comparatively high but initially such 20 pressure is much lower and rises with the temperatures until the vaporizable metal is completely volatilized at which time maximum efficiency of the lamp is obtained.

25 To enable a rapid rise in temperature the tube is usually insulated thermally by enclosing in an evacuated outer glass envelope which may be provided with a gas filling to assist in heat insulating the inner tube as well as the outer envelope forming a convenient structure for housing and supplying the electrodes of the tube with 30 electrical energy. Moreover, with tubes of the high pressure metallic vapor type it is quite difficult to initiate a discharge between the electrodes due to the low pressure and temperature.

35 To overcome such disadvantage it has heretofore been the practice to employ electrodes made of cores of alkaline earth compounds, such as carbonates, hydroxides, or silicates with or without metal mixtures. Such cores are inserted 40 in sections of highly refractory metal and the oxides activated by heating to a high temperature by the passage of an electrical discharge or in some instances by high frequency induction heating.

45 Although electrodes constructed in such manner, when energized by the passage of an electrical current, cause an initial discharge by reason of the deposit of electron emissive material, which becomes emissive even at low temperatures and pressure, together with initial ionization of the rare gases, nevertheless such electrodes are subject to certain inherent disadvantages. Since the electrodes are subjected to the high temperature and ionic bombardment 50 during operation of the tube after volatilization

of the vaporizable metal the oxide surface vaporizes and sputters shortening the life of the tube and also causing a blackening of the envelope.

It is accordingly an object of my present invention to provide an improved form of electrode for a high pressure discharge device.

5 Another object of my present invention is the provision of an electrode particularly adaptable to high pressure discharge tubes wherein a portion of the electrode supplies a copious flow of 10 electrons for initially ionizing the gaseous medium within the tube and causing a discharge and upon a rise in temperature another portion of the electrode receives the discharge during operation of the tube.

15 Another object of my present invention is the provision of an electrode particularly adaptable to high pressure discharge lamps employing a highly refractory material wherein a portion of such metal is coated with a highly emissive electron material which supplies a copious flow of 20 electrons at low temperature and pressure for initiating a discharge and upon an increase in temperature and pressure the remaining portion of the electrode of refractory material assumes 25 the discharge.

30 A further object of my present invention is the provision of an electrode comprising a helix of refractory material having a further helical winding of refractory material wound transversely to the convolutions of the helix and 35 wherein a portion of the transversely wound helical windings are coated so as to be highly electron emissive at low temperatures with the remaining portion being emissive at high temperatures.

40 Still further objects of my present invention will become obvious to those skilled in the art by reference to the accompanying drawing wherein:

Fig. 1 is a side elevational view of a discharge device including an electrode constructed in accordance with my present invention,

Fig. 2 is an enlarged side elevational view of one of the electrodes as shown in the tube of Fig. 1, and

Fig. 3 is an end view of the electrode taken on the line III—III and looking in the direction of the arrows as shown in Fig. 2.

45 Referring now to the drawing in detail I have 50 shown in Fig. 1 a high pressure discharge tube comprising a discharge chamber 5 enclosed in an outer chamber 6 which latter may be evacuated and filled with a suitable gas to thermally insulate the chamber 5. Following my present in- 55

vention an electrode 7 is sealed-in at 8 and 9 to each end of the discharge chamber. This electrode comprises a wire 10 of highly refractory material, such as tungsten, which is wound into helical form of about 40 turns per inch and, as shown more clearly in Fig. 2, may be of approximately six turns or convolutions in length. At about the center of the helix the turns or convolutions are pulled out as shown at 12, while the remaining convolutions are left in close proximity to each other. A helix of tungsten wire 13, having approximately 89 turns per inch, is slipped upon the remaining adjacent convolutions of the tungsten wire 10 at each end, which thus forms a core, so that the convolutions of the helix 13 are disposed transversely of those of the wire 10, and preferably adjacent convolutions are in contact with each other to facilitate exhausting of the tube due to the electrode being readily heated by high frequency.

As shown there is a slight spaced relation between the coils of the helix 13 providing interstices to receive a deposit of electron emissive material. Such a deposit of electron emissive material 14 is then applied to the helix 13 which is wound about the wire 10 adjacent to the envelope wall through which the wire 10 extends while the opposite end containing the remaining helix 13 is left uncoated.

This coating can be applied by dipping the electrode into a suitable solution of such material or the same may be sprayed thereupon and thus deposited in the interstices and upon the coils 13. Such coating may consist of compounds of barium, strontium, etc., or other alkali compounds which may be decomposed to oxides and activated by suitable heating, such as by high frequency induction treatment or the passage of a discharge current after the electrodes are mounted within the lamp as is well known in the

a
During operation of the lamp a suitable voltage is impressed upon the oppositely disposed electrodes and due to the copious flow of electrons from that portion of the electrodes having the coating 14 they initially cause a resulting ionization of the gas with an accompanying discharge despite the low temperature and pressure within the lamp. As the discharge continues the uncoated portion 13 of the electrode becomes heated by the discharge to an electron emitting temperature, which then assumes the discharge thus removing the same from the coated portion 14 and enabling the temperature and pressure of the lamp to increase and volatilize the vaporizable metal.

Moreover, the relatively large spacing provided by pulling out the convolutions 12 prevents to a substantial extent the heat from the uncoated portion 13 being transmitted to the coated portion 14, thus maintaining the latter comparatively cool so as to inhibit appreciable electron emission during normal operating temperature and pressure of the lamp. Also, despite the fact that the coated portion 14 of the electrode is maintained relatively cool, such has no effect upon the vapor pressure as there exists no pockets or dead space behind the electrodes.

In order, as before stated, to thermally insulate the lamp as well as form a convenient structure for housing the same it is disposed within an outer envelope 6. This latter envelope is provided with a stem 15 at one end through which pass a pair of leading-in conductors 16 and 17 sealed therein by a press 18 in a well known man-

ner. An exhaust tube 19 is also provided for the purpose of evacuating the envelope 6 and introducing a suitable gas, if desired, after which such tube is sealed off. The leading-in conductor 16 is suitably joined to the wire 10 as by welding 5 and similarly the conductor 17 extends longitudinally of the lamp 5 and may be secured to the wire 10 of the oppositely disposed electrode in a like manner. A metallic winding 20 which is electrically connected to the leading-in conductor 17 may be employed to assist in supporting this conductor and also to facilitate starting of the lamp.

It can thus be readily seen by those skilled in the art that I have provided an electrode particularly adaptable to discharge devices of the metallic vapor type wherein a portion of the electrode serves to initiate a discharge at a low temperature and pressure after which another portion of the electrode assumes the discharge 20 upon the temperature and pressure increasing during operation of the lamp. Inasmuch as that portion of the electrode which initiates the discharge is maintained comparatively cool during normal operation of the lamp and although positioned in back of the normal operating portion of the electrode the possibility of low pressure areas existing in the ends of the lamp is eliminated by an absence of pockets or dead spaces. Moreover such a lamp after operation for prolonged periods of time is free from blackening and has a reasonable low starting voltage.

Although I have shown and described one specific embodiment of my present invention I do not desire to be limited thereto as various other 35 modifications of the same may be made without departing from the spirit and scope of the appended claims.

What is claimed is:

1. An electric discharge device provided with 40 a sealed envelope and having operating electrodes extending into and sealed through the wall of said envelope, said electrodes comprising a helical winding of refractory material disposed interiorly of each end of said envelope and axially directed toward each other, a helical winding of refractory material wound transversely to the convolutions of said first mentioned helical winding, and a coating of high electron emissive material disposed upon a portion of said transversely wound helical winding positioned farthest from the oppositely disposed electrode.

2. An electric discharge device provided with a sealed envelope and having an operating electrode extending into and sealed through the wall 55 of said envelope, said electrode comprising a helix with approximately the center convolutions thereof extended to provide a relatively large spacing between the remaining convolutions at each end of said helix, a helical winding disposed transversely of the relatively closely positioned end convolutions of said helix, and a coating of electron emissive material disposed upon said transversely wound helical winding at the end of said helix in closest proximity to the 60 portion of said envelope to which said electrode is sealed.

3. An electric discharge device provided with a gaseous filling including a metal vapor and operating with a high pressure discharge comprising a sealed envelope, an operating electrode of refractory material extending into and sealed through the wall of said envelope at each end thereof and wound into a helix interiorly of said 70

- envelope and coaxially disposed relative to the longitudinal axis of said envelope, a helical winding of refractory material transversely disposed relative to the convolutions of said helix and 5 having a portion thereof disposed fartherest from the oppositely disposed electrode coated with an electron emissive material for the purpose of ionizing the gaseous filling and initiating a discharge between said electrodes upon energization thereof in order to heat the remaining uncoated portion of said electrodes to an electron emitting temperature and cause the discharge to be concentrated between the latter upon an increase in temperature and pressure of said 10 device.
4. An electric discharge device provided with a gaseous filling including a metal vapor and operating with a high pressure discharge comprising a sealed envelope, an electrode of refractory material extending into and sealed through the wall of said envelope at each end thereof and wound into a helix with approximately the center convolution thereof extended to provide a relatively large spacing between the 15 remaining convolutions at each end of said helix and to substantially prevent the transmission of thermal energy between the spiral ends of said helix during operation of said device, said electrodes including a helical winding of refractory 20 material disposed transversely of the relatively closely positioned end convolutions of said helix and having a coating of electron emissive material disposed upon said transversely wound helical winding fartherest from the opposite electrode for the purpose of ionizing the gaseous filling and initiating a discharge between said electrodes upon energization thereof in order to heat the remaining uncoated portion of said electrodes 25
- to an electron emitting temperature and cause the discharge to be shifted between the latter upon an increase of temperature and pressure of said device.
5. An electrode for a discharge device comprising a helically wound wire of refractory material having approximately the center convolution thereof extended to provide a relatively large spacing between the remaining end convolutions of said wire, a helical winding of refractory material disposed upon the relatively closely spaced end convolutions of said wire and positioned transversely of the latter, and a coating of electron emissive material disposed upon a portion of said transversely wound helical 10 winding.
6. An electrode for a discharge device comprising a section provided with an activated coating, a section consisting of a base metal, and a heat dissipating section intermediate said first 15 two mentioned sections.
7. An electrode for a discharge device comprising a section of helical form provided with an activated coating, a section consisting of a base metal of helical form, and an intermediate heat 20 dissipating section between said aforementioned sections.
8. An electrode for a discharge device comprising a refractory metal core of helical form, a section of said core being provided with a helical winding having an activated coating, a further section having a helical winding of a base metal, and an intermediate section comprising said core and having the convolutions thereof extended to 25 provide a heat dissipating section between said sections having the helical windings.

DANIEL S. GUSTIN.
